UNITED STATES PATENT OFFICE.

ALBERT WILSON OTTO, OF OSGOOD STATION, CANADA.

FEED-GUIDE FOR PRINTING-MACHINES.

SPECIFICATION forming part of Letters Patent No. 762,343, dated June 14, 1904.

Application filed May 1, 1903. Serial No. 155,208. (No model.)

To all whom it may concern:

Be it known that I, ALBERT WILSON OTTO, printer, of the village of Osgood Station, in the county of Russell, Province of Ontario, 5 Canada, have invented certain new and useful Improvements in Feed-Guides for Printing-Machines, of which the following is a specification.

My invention relates to improvements in feed-guides for printing-machines; and the objects of my invention are to devise a simple, cheap, and effective means for holding the edge of a piece of paper on the platen of the printing-machine, so that when the 15 printing is done it will come in the right position upon the paper, further objects being to construct the device in such manner that it may be used as an extension feed-guide—that is, one extending beyond the edge of the 20 platen, so as to both support and guide the paper—and to make the device in such a way that it will not injure the platen-sheet or tear it when being used; and it consists, essentially, 25 of a holder comprising a horizontal portion and a downwardly-extending flange adapted to be gripped between the platen and the bail and a strip slidably held on said horizontal portion and having guiding means at one end, the various parts of the device being constructed and arranged in detail, as hereinafter more particularly described.

Figure 1 is a perspective view of a platen of a printing-machine, showing my feed-guides in use. Fig. 2 is a section through one of the 35 feed-guides and the platen. Fig. 3 is a perspective view of the platen of a printing-machine with two of the devices with attachments enabling them to be used as extension feed-guides. Fig. 4 is a section through one 40 of the feed-guides and the platen, as shown in Fig. 3. Fig. 5 is a perspective view of the feed-guide, the strip being reversed in its holder, and the whole being reversed in such a manner that it may be used as an extension 45 feed-guide.

In the drawings like letters of reference indicate corresponding parts in each figure.

A is the platen of a printing-machine.

B is the bail which surrounds the platen, 50 and C is the platen-sheet, which is a sheet of

paper spread over the surface of the platen and held in place by the bail.

D is a stiff strip of any suitable material, such as sheet brass, steel, or the like. This strip is formed at its end with a downwardly-extending flange d, which is preferably wider than the strip, and the lateral extremities thereof are slightly bent backward, as shown, to prevent the edges of the paper from being caught thereby. A projection d' extends forwardly from the upper central portion of the flange d, and this projection may be made in any suitable way, but is preferably stamped out of the end portion of the strip D and bent around, as shown. The strip D is provided with a suitable securing device by which it may be held in position on the platen. The device which I prefer to employ for this purpose consists of the plate E, having a downwardly-extending flange e formed at one end 70 thereof and adapted to extend between the platen and the bail. At the forward or opposite end of this plate guides e' e' are formed, preferably by bending up a portion of each side of the plate. The rear end of the strip 75 D is held in these guides with sufficient friction to prevent its moving therein longitudinally unless actually moved by hand.

It will now be seen that when one or more of the devices as above described is or are secured to the platen, the flanges d being in alinement, a piece of paper upon which printing is to be done may be placed with its edge along the alinement of the flanges d in such a manner that it will be brought into the correct position and all other similar pieces could be printed in an exactly similar way, or, in other words, with a margin of equal width.

It is frequently desirable to leave a margin on the paper to be printed of such a width 90 that the paper becomes wider than the platen. It is obviously necessary in such a case to provide guides which will extend beyond the edge of the platen and support the paper and at the same time hold its edge at the proper 95 distance and in the proper alinement. My device may be used in this way (see Fig. 5) by simply pulling out the strip D from the guides e' and inserting it in them from the opposite end, at the same time reversing the 100

plate E, so that it will extend beyond the edge of the platen. It is preferable, however, when using the device as an extension feed-guide to provide additional attachments—namely, a 5 supporting-piece F and an adjustable guide G. (See Figs. 3 and 4.) The supporting-piece F consists of a body having upwardly-turned sides forming the guides f and a downwardly-extending flange f', adapted to fit in between 10 the bail and the platen, thereby forming a support. The slideable guide G, which is adapted to be attached to the strip D, consists of a flat portion g, having the lower edges bent downwardly and inwardly to form guides for 15 the edges of the strip D. A forward upright portion or flange g' is formed thereon with an overhanging lip g'', which is adapted to hold down the edge of the paper to be printed on in the same manner as the projection d' acts 20 when the guide is being used, as shown in Figs. 1, 2, and 5.

It will now be seen that I have devised an extremely cheap, simple, light, and easily-operated feed-guide for printing-machines. In 25 feed-guides used in the past there were a number of disadvantages which were difficult to overcome. For instance, the method of securing the guides generally necessitated the use of spikes or pins, which had to be forced into 30 the paper of the platen, the result being that the platen-sheet had to be renewed very frequently, as it became torn after a very short period of use. They were complicated and expensive, and separate feed-guides had to be 35 employed when it was necessary to have an extension feed-guide, and a further disadvantage was that the extension feed-guides were generally made so heavy that it was necessary to bend the securing-piece completely 40 round the bail, so that they could not be removed without unbending such securing-piece, and the bending and unbending very soon would cause a break, with consequent inconvenience and expense. It will be 45 seen, however, that my device obviates all these difficulties. It is simple and cheap in construction, may be adjusted to any desired position, and may be used both as an extension and as an ordinary feed-guide. It is sufficiently 50 light to be supported by a supporting-piece, which is simply inserted between the bail and the platen without bending, and

has numerous other advantages, such as the rapidity of adjustment, &c., which need not be further enlarged upon.

It is to be understood that in placing this invention on the market slight alterations may be made in the construction and arrangement of the various parts without departing from the spirit of my invention. For example, the 60 form of the securing-piece E might be altered in detail, also the form of the strip D and of the guiding-piece G; but it is to be understood that I do not wish to be limited to the form as shown and described. 65

What I claim as my invention is—

1. In a device of the class described, the combination with the holder comprising a horizontal portion having guides at the sides thereof and a vertical portion or flange adapted to extend between the platen and the bail, of a strip slidably held in the guides, said strip being provided at one end with a downwardly-extending face or flange of greater width than the strip, the lateral extremities of said flange being bent rearwardly and a tongue centrally located at the forward end of the strip and extending forwardly beyond the vertical face or flange as and for the purpose specified. 75

2. In a device of the class described, the combination with a holder comprising a horizontal portion provided with guides and a vertical portion adapted to extend between the platen and the bail, of a strip slidably secured in said guides and adapted to extend outwardly 80 beyond the platen, a guide slidably secured to the said strip and comprising a horizontal portion having guides formed at the sides thereof to engage the edges of the strip, a vertical guiding face or flange at the forward end of 85 said horizontal portion and of greater width than the horizontal portion, the lateral extremities of said vertical flange curving rearwardly and an overhanging centrally-located tongue or upper guide extending forwardly 90 and upwardly from the upper edge of the vertical flange or face as and for the purpose specified. 95

Signed at Ottawa, in the Province of Ontario, this 27th day of April, 1903.

ALBERT WILSON OTTO.
